UNITED STATES PATENT OFFICE.

CHARLES G. CARLSON, OF CHICAGO, ILLINOIS.

CURTAIN-STRETCHER.

SPECIFICATION forming part of Letters Patent No. 701,014, dated May 27, 1902.

Application filed December 9, 1901. Serial No. 85,159. (No model.)

To all whom it may concern:

Be it known that I, CHARLES G. CARLSON, a citizen of the United States, residing at Chicago, in the county of Cook and State of Illinois, have invented a certain new and useful Improvement in Curtain-Stretchers, of which the following is a specification.

The invention relates to that class of curtain-stretchers having divided side bars or rails adapted to fold edgewise at the joint, with end bars or rails attached to the side bars or rails at the corners by means of suitable clamping-bolts, so as to be adjustable for changing the length and width of the stretcher, and having a central cross bar or brace for giving rigidity to the side bars or rails at the joint and preventing the inward curving or bending of the side bars or rails in use.

The objects of the invention are to simplify and improve the connection of the side bars or rails at the joint, so as to enable the side bars or rails to be folded each on itself edgewise readily and quickly and so as to permit of the folding of the side bars or rails onto the cross-bar one over the other and placing on the folded side bars or rails the end bars or rails, making a compact folding of the stretcher or frame for shipment or storing away when out of use; to improve the plate connecting the divided side bars or rails at the joint and forming the abutting ends of the sections or divisions of each side bar or rail, so as to permit of the folding together edgewise of the sections or divisions, and when unfolded have the joint at the division-line firm and strong; to furnish a pivotal connection for the abutting ends of the divided side bars or rails through the connecting and stiffening plate which will enable one of the side bars or rails to be elevated without breaking the pivotal connection for the passing thereunder of the sections of the other side bar or rail in folding the stretcher into a small compass, and to improve generally the construction and operation of the curtain-stretcher as a whole.

The invention consists in the features of construction and combinations of parts hereinafter described and claimed.

In the drawings, Figure 1 is a top or plan view showing the stretcher open in condition for use; Fig. 2, an edge elevation of the

stretcher open as in Fig. 1; Fig. 3, a top or plan view showing the divided side bars or rails partially folded one underneath the other on top of the cross-brace or stiffening-bar; Fig. 4, a top or plan view with the divided side bars or rails completely folded one under the other on top of the cross-brace or stiffening-rod; Fig. 5, a top or plan view with the end bars or rails placed on the folded side bars or rails and held in place by the corner clamping-bolts; Fig. 6, a side elevation of the folded curtain-stretcher frame with the parts together as in Fig. 5, and Fig. 7 an end elevation of the folded frame with the parts together as in Fig. 5.

The curtain-stretcher has the side bars or rails A and A', divided at the center, each section or division of each bar or rail being of equal length, and each bar or rail at its end in the arrangement shown has a slot a, permitting of the endwise adjustment of the end bars or rails. The end bars or rails B each have a longitudinal slot b in one end, and the other end is provided with a hole b', as shown, suitable for the passage of the clamping-bolts. A clamping-bolt C is provided for the crossing corners of the side bars or rails and the end bars or rails, the clamping-bolt at two of the corners passing through the slots a and b of the side bar or rail and the end bars or rails and at the other corners passing through the slots of the side bar or rail and the hole in the end of each end bar or rail. Each clamping-bolt has a winged nut, with thumb or finger pieces or wings c and a broad base c', so that by tightening the winged nuts the clamping-bolts will operate and firmly unite the crossing corners of the bars or rails. A cross-brace or stiffening-bar D of a length corresponding to the length of the end bars or rails extends from side rail to side rail, overlapping the joint of each bar or rail at the abutting ends of its sections, and this cross-brace or stiffening-bar has in one end a slot d and in the opposite end a hole (not shown) for the passage of the clamping-bolts which unite the cross-brace or stiffening-bar to the side bars or rails. The cross-brace or stiffening-bar is on the under side of the side bars or rails, overlapping the joints at the abutting ends, and on the opposite face of each side bar or rail is a stiffening-plate E,

having its side edges *e* turned so as to overlap the edge of the side bar or rail and furnish a bearing on top and each side of the bar or rail at the joint of the abutting ends. A 5 clamping-bolt *F* passes through the slot *d* of the cross-brace or stiffening-bar and through the hole between the abutting ends of the side bar or rail *A*, formed by semicircular recesses *a*² in the end face of the abutting ends, as 10 shown in Figs. 3 and 4, and this clamping-bolt is of a greater length than the united depth of the thicknesses of the sections of the side bars or rails when folded together, so as to allow the side bar or rail *A* to be raised 15 or lifted above the face of the cross-brace or stiffening-bar a sufficient distance to leave a space in which to enter the sections of the side bar or rail *A'* in folding the frame. A 20 clamping-bolt *F'* passes through the hole therefor in the end of the cross-brace or stiffening-bar and through a hole formed in the abutting ends of the sections of the side bar or rail *A'* by semicircular recesses *a*² in the 25 face of the abutting ends, the same as described for the abutting ends of the side bar or rail *A* for the passage of the clamping-bolt *F* of said bar, and this clamping-bolt *F'* is of a sufficient length to pass through the end 30 of the cross-brace or stiffening-bar and the side bar or rail, and the clamping-bolt projects the required distance for receiving a 35 tightening-nut and permit of the withdrawal of the nut the distance required for raising the stiffening-plate, so as to have its side edges or flanges *e* clear the face of the side bar or rail, and allows the sections of the side bar or rail to be turned edgewise toward each other, and this is also true of the clamping-bolt *F* so far as concerns the release of its 40 nut to raise the stiffening-plate for its side edges or flanges to clear the face of the side bar or rail *A* and permit the folding of the sections of the side bar or rail edgewise on themselves inwardly in addition to the length 45 required for the bolt *F* to permit of the raising or lifting of the side bar or rail *A* to leave the space for the admission of the side bar or rail *A'* in folding the frame. Each clamping-bolt *F* and *F'* has a winged nut, with side 50 pieces or wings *f* and a center *f'*, which when the nut is down to place abuts against a boss or raised portion *e'* on the face of each stiffening-plate, so as to give a solid bearing for the clamping-bolts in tightening the cross- 55 brace or stiffening-bar to the side bars or rails.

The stiffening-plate *E* for the side bar or rail *A* has depending from its underside near each end a pivot or pin *G*, and each pin or pivot *G* passes through the abutting ends of the sections 60 of the side bar or rail and furnishes a pivotal connection between the stiffening-plate and the abutting ends of the side bar or rail, permitting the sections of the side bar or rail to fold and unfold edgewise in closing and 65 opening the side bar or rail. These pins or pivots *G* each have a head *g* and each is of a length to allow of the raising or lifting of

the stiffening-plate above the face of the bar or rail and leave a space of a depth to clear the thickness of the plate and its edge from 70 the face of the bar or rail for folding edgewise, and the heads *g* prevent the entire withdrawal of the pins or pivots in raising or lifting the two sections of the side bar or rail *A* for the entrance between the side bar or rail and the cross-brace or stiffening-bar of the sections of the divided bar or rail *A'* when folded edgewise. The stiffening-plate *E* for the joint of the divided side bar or rail *A* has at each end a depending pin or pivot *G'*, similar to the pins or pivots *G*, except being shorter and having no heads, the heads being unnecessary for the pins or pivots *G'*, as it is not required to raise the abutting ends of the side bar or rail in folding the sections 85 thereof onto the cross-brace or stiffening-bar. The side bars or rails and the end bars or rails each have on the inner edge a rabbeted or depressed portion *h*, through which in the construction shown from the under side are 90 driven the retaining-pins *i* for the attachment of the curtain or other article to be placed on the frame when extended.

The curtain-stretcher in use has the side bars or rails *A* and *A'* extended and the end 95 bars or rails attached thereto at the crossing corners by the clamping-bolts and the cross-brace or stiffening-bars attached over the joints at the abutting ends of the side bars or rails, and the side bars or rails and the 100 end bars or rails are adjusted through the medium of the slots in their ends, so as to set the frame for the size of the curtain or other article to be placed on the stretcher. The frame is folded into a compact form by 105 removing the nuts of the corner clamping-bolts and withdrawing such bolts, so as to detach the end bars or rails. The clamping-nuts of the bolts *F* and *F'* are loosened or receded a sufficient distance for the lifting or 110 raising of the respective stiffening-plates over the joints of the divided side bars or rails, the nut of the bolt *F* being receded so as to permit of the lifting or raising of the side bar or rail *A* a sufficient distance to enter between the sections of said bar or rail, when folded edgewise on itself, the sections of the side-bar or rail *A'* which fold over the cross-brace or stiffening-bar. The sections of the bar or rail *A'* are folded edgewise inwardly, 115 turning on the pins or pivots of the stiffening-plate to overlie the cross-brace or stiffening-bar, and the sections of the side bar or rail *A* are folded edgewise inwardly over the sections of the side bar or rail *A'*, turning on the 120 pins or pivots of the stiffening-plate of such bar to pass over the sections of the divided bar or rail *A'* for their free ends to pass over the stiffening-plate of the bar or rail *A'*. The manner of folding the sections of the side 125 bars or rails is shown in Fig. 3, and in order to permit of the close folding of the sections of the bar or rail *A* the inner edge of the sections on the inside are each cut out, so as to

leave an edgewise depression a^3 , which permits the free ends to clear the head of the winged nut for the sections to lie parallel with and over the sections of the bar or rail 5 A', as shown in Fig. 4, in which figure the side bars or rails are completely folded for the sections of the bar or rail A' to lie on the cross-brace or stiffening-bar and the sections of the bar or rail A to overlie the sections of 10 the bar or rail A', making a package of a length equal to the length of the section of the bar or rail and of a width slightly greater than twice the width of the bar or rail. The end bars or rails are placed in position one over 15 each section of the side bars or rails, and the corner clamping-bolts C are passed through the slot a of a section of the side bar or rail A and through the slot b of the end bar or rail and the clamping or winged nuts threaded onto 20 the ends of the clamping-bolts, securing the end bars or rails on the folded side bars or rails, as shown in Figs. 5, 6, and 7, making a close and compact bundle or package which can be stored away without occupying much 25 room and which is in the best possible shape for transportation or shipment. The side bars or rails folded edgewise inwardly bring the retaining-pins on the inside, where they will be protected, and in placing the end bars or 30 rails in position the bars or rails are turned to have their under face on top, which brings the retaining-pins of such bars or rails downwardly on the inside, so that when in a folded condition the retaining-pins are all on the inside and fully guarded and protected against 35 injury. The stiffening-plates when the stretcher has its frame folded lie crosswise of their respective folded side bars or rails, with the turned edges or flanges resting on 40 the face of the bars or rails, as shown in Fig. 7, and preferably the length of each stiffening-plate is approximately the same as the width of the side bars or rails when folded, so as to leave but little, if any, projecting ends 45 of the stiffening-plates, as shown in Figs. 4 and 5. The turning or folding of the sections of each side bar or rail inwardly edgewise is permitted by rounding the inner corners of 50 the abutting ends of the sections of the bar or rail, so as to leave a curved corner a' for the folding and unfolding of the sections, and when opened out the abutting ends contact each other on their straight portions, so that when the stiffening-plate is brought down to 55 position a firm and solid joint is formed, and the folding and unfolding movement is attained through the pins or pivots depending from the stiffening-plates and passing down between the abutting ends of the bar or rail 60 sections.

The construction is very simple, the stiffening-plates, with their depending pins or pivots, furnishing a means for giving rigidity to the joint between the abutting ends of the 65 side bars or rails and also forming a pivotal connection for folding and unfolding the sections. The lengthening of one of the clamp-

ing-bolts for attaching the cross-brace or stiffening-bar to the side bar or rail enables the side bar or rail to be raised for its sections to overlie the sections of the other bar or rail when the bars or rails are folded edgewise inwardly, and this raising or lifting without detachment is permitted by the stops on the pins or pivots of the stiffening-plate for 70 the bar or rail to be raised. The frame can be quickly and easily brought into condition to be folded, requiring only the removal of the corner clamping-bolts and the withdrawal of the end bars or rails, loosening the clamping-bolts for the cross-brace or stiffening-bar, raising one of the side bars or rails, folding the sections of the side bars or rails edgewise inwardly to overlie each other on the cross-brace or stiffening-bar, placing 75 the end bars or rails bottom upward on the folded sections of the side bars or rails, passing the corner clamping-bolts through the slots of one of the side bars or rails and the end bars or rails, and applying and setting 80 down the nuts of the clamping-bolts, and when folded, if desired, for shipment the folded frame can be secured against displacement or movement edgewise of the bars or rails by tying bands or cords or otherwise. 85 The construction is one which enables the frame to be folded up for shipment or storing away and to be readily unfolded and extended for use, and to unfold and extend the frame for use it is only necessary to withdraw the 90 nuts of the corner clamping-bolts, remove such bolts from the slots, take away the end bars or rails, open out or extend the sections of the side bars or rails, place the end bars or rails underneath the ends of the opened side 95 bars or rails, pass the corner-bolts through the slots, apply the nuts, adjust the bars to the desired position, and tighten the clamping-bolts for the corners and the clamping-bolts for the cross-brace or stiffening-bar, 100 making the frame in its extended position rigid and firm for the reception of the curtains or other articles.

What I regard as new, and desire to secure by Letters Patent, is—

1. In a curtain-stretcher, the combination of divided side bars or rails edgewise folding a stiffening-plate for the joint of each side bar or rail overlapping the abutting ends of the bar or rail sections on each side of the joint, depending pins or pivots for each stiffening-plate, one pin or pivot at each end of the plate, the pins or pivots of one plate having a greater length than the thickness of the bar or rail and each provided with a stop 120 on its lower end, a cross-brace or stiffening-bar extending from side bar or rail to side bar or rail and crossing the bars or rails at the joints on the opposite face of the bar or rail to the stiffening-plate, clamping-bolts one for each end of the cross-brace or stiffening-bar, passing through the cross-brace or stiffening-bar, between the abutting ends of the sections of the side bar or rail, and through the 125 130

stiffening - plate one bolt having a greater length than the combined thickness of the cross-brace or stiffening-bar and the two side bars or rails when folded, and tightening-nuts for the clamping-bolts, substantially as described.

2. In a curtain-stretcher, the combination of divided side bars or rails edgewise folding a stiffening-plate for the joint of each side bar or rail overlapping the abutting ends of the bar or rail sections on each side of the joint and having on each side depending edges or flanges engaging the side faces of the bar or rail, depending pins or pivots for each stiffening-plate, one pin or pivot at each end of the plate the pins or pivots of one plate having a greater length than the thickness of the bar or rail and each provided with a head, a cross-brace or stiffening-bar extending from side bar or rail to side bar or rail and crossing the bars or rails at the joints on the opposite face of the bar or rail to the stiffening-plate, clamping-bolts, one for each end of the cross-brace or stiffening-bar, passing through the cross-brace or stiffening-bar, between the abutting ends of the sections of the side bar or rail, and through the stiffening-plate, one bolt having a greater length than the combined thickness of the cross-brace or stiffening-bar and the two side bars or rails when folded, tightening-nuts for the clamping-bolts of the cross-brace or stiffening-bar, end bars or rails, and clamping-bolts for the crossing corners of the side bars or rails and the end bars or rails, substantially as described.

3. In a curtain-stretcher, the combination of divided side bars or rails edgewise folding, each bar or rail at its abutting end having a rounded inner corner and a semicircular recess, a stiffening-plate for the joint of each bar or rail overlapping the abutting ends of the bar or rail sections on each side of the joint, depending pins or pivots for each stiffening-plate, one pin or pivot at each end of the plate, the pins or pivots furnishing a pivotal connection between the sections of the divided side bar or rail, permitting, in conjunction with the rounded inner corner at the abutting ends of the sections, the edgewise folding of the sections of the divided side bar or rail, a cross-brace or stiffening-bar extending from side bar or rail to side bar or rail and crossing the bars or rails at the joints on the opposite side of each bar or rail to the stiffening-plate, clamping-bolts one for each end of the cross-brace or stiffening-bar passing through the cross-brace or stiffening-bar and the semicircular recesses in the abutting ends of the sections of the side bar or rail and through the stiffening-plate, and tightening-nuts for the clamping-bolts, substantially as described.

4. In a curtain-stretcher, the combination of divided side bars or rails edgewise folding each section of each bar or rail at the abutting ends having a rounded inner corner, a stiffen-

ing-plate for the joint of each side bar or rail overlapping the abutting ends of the bar or rail sections on each side of the joint and having on each side depending edges or flanges engaging the side faces of the bar or rail, depending pins or pivots at each end of the plate, the pins or pivots furnishing a pivotal connection between the sections of the divided side bar or rail, permitting, in conjunction with the rounded inner corners at the abutting ends of the sections, the edgewise folding of the sections of the divided bar or rail, a cross-brace or stiffening-bar extending from side bar or rail to side bar or rail and crossing the bars or rails at the joints on the opposite side of each bar or rail to the stiffening-plate, and clamping-bolts, one for each end of the cross-brace or stiffening-bar, passing through the cross-brace or stiffening-bar, between the abutting ends of the sections of the side bar or rail, and through the stiffening-plate, for drawing together the cross-brace or stiffening-bar and the abutting ends of the side bar or rail and forcing the stiffening-plate against the face of the bar or rail on each side of the joint, substantially as described.

5. In a curtain-stretcher, the combination of divided side bars or rails edgewise folding, each bar or rail at its abutting end having a rounded inner corner, a stiffening-plate for the joint of each bar or rail overlapping the abutting ends of the bar or rail sections on each side of the joint, depending pins or pivots for the stiffening-plate, one pin or pivot at each end of the plate and the pins or pivots of one plate having a greater length than the thickness of the bar or rail and each provided with a stop on its lower end, a cross-brace or stiffening-bar extending from side bar or rail to side bar or rail and crossing the bars or rails at the joints on the opposite face of the bar or rail to the stiffening-plate, clamping-bolts, one for each end of the cross-brace or stiffening-bar, passing through the cross-brace or stiffening-bar between the abutting ends of the sections of the side bar or rail and through the stiffening-plate, one bolt having a greater length than the thickness of the cross-brace or stiffening-bar and the two side bars or rails when folded, tightening-nuts for the clamping-bolts of the cross-brace or stiffening-bar, detachable end bars or rails and removable clamping-bolts for the crossing corners of the side bars or rails and the end bars or rails, for folding the divided side bars or rails edgewise one over the other and on the cross-brace or stiffening-bar and placing the end bars or rails on the folded sections of the side bars or rails and thereby folding the stretcher, as a whole, in a compact form for shipment and storing away with the retaining-pins protected, substantially as described.
